(57) **CLAIM**

The ornamental design for a horizontal and vertical cable holder, as shown and described.

DESCRIPTION

FIG. 1 is a perspective view of a horizontal and vertical cable holder according to our design;

FIG. 2 is a front elevation view of the design shown in FIG. 1;

FIG. 3 is a back elevation view of the design shown in FIG. 1;

FIG. 4 is a left side elevation view of the design shown in FIG. 1;

FIG. 5 is a right side elevation view of the design shown in FIG. 1;

FIG. 6 is a top plan view of the design shown in FIG. 1;

FIG. 7 is a bottom plan view of the design shown in FIG. 1; and,

FIG. 8 is another perspective view of the design shown in FIG. 1, in which the broken line showing of the environment is included for the purpose of illustrating the design in a condition of use and forms no part of the claimed design.
